UNITED STATES PATENT OFFICE.

HOWARD OAKLAND, OF HOQUIAM, WASHINGTON.

TIE-DISPLAY FIXTURE.

1,236,342.

Specification of Letters Patent.

Patented Aug. 7, 1917.

Application filed March 9, 1916. Serial No. 83,117.

To all whom it may concern:

Be it known that I, HOWARD OAKLAND, a citizen of the United States, residing at Hoquiam, in the county of Grays Harbor and State of Washington, have invented certain new and useful Improvements in Tie-Display Fixtures, of which the following is a specification, reference being had therein to the accompanying drawing.

10 This invention relates to certain new and useful improvements in display fixtures and more particularly to that class of invention known as "tie display fixtures", the object being to provide a display fixture so constructed that a large number of neckties can be displayed in such a manner that the purchaser can readily inspect the same.

Another object of the invention is to provide a display fixture which is very compact in form and by means of which, a large number of ties can be displayed in a small space and in such a manner that the ties supported thereby, do not have to be handled and re-handled by the purchaser, thereby decreasing the work of the salesmen.

Another object of my invention is to provide a display fixture in which a tubular member is employed in connection with a tray portion, the tubular member being adapted to receive the folded portion of a tie so as to support the same in such a manner that the tip of the ties can be spread out to allow the purchaser to readily inspect the same.

Another and further object of the invention is to provide a display fixture which is exceedingly simple and cheap in construction and one which can be formed of various kinds of material.

Other and further objects and advantages of the invention will be hereinafter set forth and the novel features thereof defined by the appended claims.

45 In the drawings—

Figure 1, is a perspective of my improved construction of tie display fixtures showing a number of ties in position thereon;

Fig. 2, is a longitudinal vertical section 50 through the same;

Fig. 3, is a top plan view; and

Fig. 4, is a detail perspective of a portion of the tray showing the extension and manner of slidably connecting the same to the 55 central portion thereof.

Like numerals of reference refer to like parts in the several figures of the drawings.

In carrying out my invention, I employ a base member 1 herein shown substantially triangular in shape, having a tubular-shaped member 2 extending obliquely upwardly therefrom, said tubular-shaped member having an oval-shaped bottom 3 arranged within the lower end thereof, and secured therein by fastening members 4.

60 The bottom 3 of the tubular member is secured to the base 1 by screws 5 as shown in Fig. 2, so as to securely connect the two together.

70 The tubular member is oval-shaped in cross section and has its upper edge cut away to form tongues 6 and 7, the tongue 7 being provided with a shoulder 8 forming a stop for the ties, as will be hereinafter fully described.

75 Pivotedly mounted on the under side of the base 1 are extensible members 9 and 10 provided with side flanges 11 and 12, said base and extensible members forming a tray to receive the tip of the ties as will be hereinafter fully described.

80 As herein shown, the extensible members 9 and 10 are mounted on screws 13 and 14 extending through said extensible members into the base and the bottom portion 3 of the tubular member, but it is, of course, understood that these extensible members can be pivotally mounted in various ways and I do not wish to limit myself to any exact manner of mounting the same.

90 The extensible members 9 and 10 are provided with curved slots 15 and 16 through which extends, rivets 17 and 18 carried by the base for guiding the extensible members and while I have shown rivets for slidably connecting these two members together, I do not wish to limit myself to any particular manner of connecting the same, the main object to be accomplished, being to provide a fixture with a tray having extensible members which can be extended so as to increase the size of the tray so as to receive and support the ties in such a manner that they can be spread out in order to display the individual ties to facilitate disposing of the same.

100 In use, a number of ties are first folded midway of their lengths and the folded portions are forced down into the open end of the tubular member.

The tips of the ties are then spread so as to display a portion of each tie and it will be noted that the lip 6 forms a stop so as to prevent the folded mass of ties from riding 5 or moving in one direction, and the lip 7 together with the shoulder 8 forms a stop for limiting the movement of the ties in the other direction and while in Fig. 1, I have shown the ties spread laterally, it is, of course, understood that in actual use the ties 10 are spread so as to completely conceal the tray portion and the greater portion of the tubular portion of the display fixture, and as the ties are sold from the fixture, the extensible members can be forced toward each 15 other so as to reduce the size of the tray.

From the foregoing description, it will be seen that I have provided a display fixture in which a tray is employed having a tubular member extending obliquely therefrom adapted to receive and hold a number of ties so that the end portions of the ties can be 20 spread out in a fan-like manner for displaying the same, the folded portions of the ties being held within the tubular portion by friction. 25

I claim:

1. A display fixture, comprising a tray having extensible members, and a tubular 30 supporting member extending upwardly from said tray.

2. A display fixture, comprising a tray, a tubular member extending obliquely upwardly from said tray, said tubular member having its upper edge cut away to form oppositely disposed lips. 35

3. A display fixture, comprising a tray, comprising a central portion having extensible members pivotally connected thereto, a tubular member secured to said central 40 member, said tubular member having its upper edge cut away to form oppositely disposed lips.

4. A display fixture, comprising a tray 45 formed of a central member having ex-

tensible members pivotally connected thereto, said extensible members being provided with slots, members carried by the central member extending through said slot for guiding said extensible members, and a 50 tubular support extending obliquely from said central member.

5. A display fixture, comprising a tray comprising a central member having extensible members pivotally connected thereto, said extensible members being provided with side flanges, means for guiding said extensible members adjacent their ends, and a tubular member extending obliquely from 55 said central member. 60

6. A necktie display fixture, comprising a tray having extensible members, a tubular member having a bottom member secured therein, means passing through said tray for securing said bottom member to said tray, said tubular member being adapted to receive ties. 65

7. A display fixture, having a tray for supporting the free ends of neckties, and a tubular member for retaining the folded 70 portions of said ties. 75

8. A necktie display fixture, comprising a tray, a tubular supporting member extending obliquely upwardly from said tray, having an open end adapted to receive neckties for supporting said ties in display position. 75

9. A necktie display fixture, comprising a tray having extensible members movably connected thereto, a tubular member extending obliquely upwardly from said tray, said tubular member having its upper edge cut away to form oppositely disposed tongues, 80 said tongues forming stops for the ties when arranged therein.

In testimony whereof I hereunto affix my 85 signature in the presence of two witnesses.

HOWARD OAKLAND.
